SPRING WHEEL

Edward Stift, St. Louis, Mo.

Application November 8, 1943, Serial No. 509,383

3 Claims. (Cl. 152—6)

This invention relates to spring wheels for vehicles.

An object of this invention is to provide an improved resilient wheel which is durable, economical and efficient. Its advantages will be apparent from the following description taken in connection with the accompanying drawings.

Fig. 1 is an elevational view of a wheel embodying this invention;

Fig. 2 is a view similar to Fig. 1, taken from a side opposite that of Fig. 1;

Fig. 3 is a detail elevational view, partly in section;

Fig. 4 is a section on line 4—4, Fig. 3;

Fig. 5 is a section on line 5—5, Fig. 4;

Fig. 6 is a section on line 6—6, Fig. 5;

Fig. 7 is a section on line 7—7, Fig. 5;

Fig. 8 is a section on line 8—8, Fig. 5;

Fig. 9 is a detail sectional view on a plane at a right angle to that of Fig. 5;

Fig. 10 is an elevational view showing a sleeve employed in the wheel;

Fig. 11 is an end view of the sleeve; and

Fig. 12 is a section on line 12—12, Fig. 3.

The wheel includes a central casing 1, through the circumferential periphery of which a plurality of radial spokes 2 extend. The spokes 2 are resiliently supported by means which will be described. The wheel may be mounted on an axle 3 and has a rim 4.

The casing 1 has a pair of side walls 5 and 6 and a peripheral wall 7. As specifically shown, the peripheral wall 7 is a continuation of the wall 5, while the wall 6 is a removable plate. The casing has a fixed inner annulus 8, which with the peripheral wall 7 fix the position of the spokes.

The casing 1 has a hub 9 which may be of any desired character. It is shown conventionally in the drawings and it may be mounted directly upon the axle 3, or it may be of a form corresponding to that now commonly used in demountable wheels for automobiles.

The cover plate or wall 6 is attached to the casing by screws 10 which pass through the plate and engage the wall 7 and the annulus 8, or more particularly the flanges 11 and 12 respectively. A gasket 13 is interposed between the plate 6 and the flange 11, and a gasket 14 is interposed between the plate 6 and the flange 12.

A central floating ring 15 is positioned in the casing by the side walls and provides a novel element in a novel combination by which resiliency is secured and distributed. The inner ends of the spokes 2 or telescopic extensions thereof en-

gage the outer surface of the ring 15 so that the resilient mountings of spokes counteracts the pressure exerted on the outer ends of other spokes, the ring 15 being free to move in a single plane inside the casing except as yieldingly restrained by the spokes.

The spoke assembly may now be explained. It has already been noted that a spoke assembly, all of which are alike, is positioned by the circumferential wall 7 and the inner annulus 8 with the inner end of the assembly bearing against the floating ring 15 and the outer end attached to the rim 4.

The spoke assembly includes a tubular member 16 which has a head 17 extending beyond the circumferential wall 7 of the casing, while the shank extends inwardly through the annulus 8 and passes through a cylinder 18 fixed between the wall 7 and the annulus 8, as clearly shown in Figs. 4 and 5. A collar 19 is secured to the inner end of the spoke member 16 and limits the outward movement of the spoke, which outward movement is urged by a spring 20 having one end bearing against a shoulder formed by the head 17, and the other end bearing against the annulus 8. It may now be understood that the spoke 17 is resiliently held in its outer position by the spring 20 with the edge of the collar 19 against the inner surface of the annulus 8.

The head 17 fits the cylinder 18 while the shank passes through and fits in an appropriate circular opening 21 in the annulus. A sleeve 22, shown separately in Figs. 10 and 11, forms the inner end of the spoke assembly and bears directly against the floating ring 15. It has a circular portion which fits over the collar 19 and also has outwardly extending arms 23 which pass through arcuate slots 24 in the annulus 8 and bear against the inner end of the spring 20.

The action of the spring assembly may now be understood from the foregoing description. As pressure is exerted on the rim of the wheel at a particular spoke, that spoke will be pressed inwardly against the action of the spring 20. The member 16 will tend to move inwardly telescoping the sleeve 22 until the inner end of the member 16 bears against the floating ring 15. It will be understood that there will be a compression of the spring 20 from both ends, since the end of the arms 23 of the sleeve 22 bears against the inner end of the spring 20 while the head 17 of the member 16 exerts pressure on the outer end of the spring.

The action is not, however, limited to a par-

ticular spoke against which the pressure is applied, but the pressure is extended to other spokes through the ring 15. That is to say, when pressure is exerted at the outer end of a particular spoke, that pressure is in part absorbed by the spring 20 of that particular spoke assembly, while some of the pressure is exerted on the ring 15 and transmitted to other spoke assemblies, to the greatest extent on the spoke assembly directly opposite the one upon which the primary pressure is applied. The ring 15 tends to move with the pressure applied on the rim, and is restrained by the springs of the opposing assemblies in a manner which will be obvious from the foregoing description and the drawings.

The casing 1 is filled with oil, and to produce a dampening effect the cylinder 18 is provided with openings 25 and 25'. Since the cylinder 18 will also be full of oil, the openings 25 and 25' will slow the action of the spoke assembly. The openings 25 are placed just inwardly of the inner end of the head 17 which fits the cylinder 18, so that the initial movement of the spoke may be relatively fast. As soon, however, as the member 16 is pressed sufficiently for the head 17 to cover the openings 25, a single opening 25' will control the further action of the assembly.

The floating ring 15 may be rigid, or it may be somewhat resilient. When resilient that resiliency will aid in the entire resiliency of the wheel, and will itself absorb some of the shock as well as distribute the shock to a greater extent among the spoke assemblies.

The rim 4 must necessarily be yielding, and as specifically shown is constructed of a series of laminations, preferably of spring steel. These laminations are held together by lugs 26 on outer leaves which are bent underneath the inner laminations and by screws 27 passing through the laminations and entering the head 17. A tire 28 is placed upon the rim.

Various changes may be made in the details of construction, within the scope of the appended claims, without departing from the spirit of this invention and parts of the invention may be used without the whole.

I claim:

1. In a resilient vehicle wheel the combination comprising a plurality of radial spoke assemblies each assembly including a radial liquid containing cylinder fixed in the wheel, an outer member

formed as a piston within the cylinder and bearing against a rim of the wheel, an inner member movable radially, resilient means for urging outwardly the outer member and for urging inwardly the inner member, a restricted port in the cylinder whereby movement of the piston is damped, and a central floating ring whose periphery provides a seat for the inner end of said inner members on the spoke assemblies.

2. In a resilient wheel the combination comprising a circular casing having a pair of parallel side walls, a circular peripheral wall and a fixed inner annulus coaxial with the peripheral wall, a plurality of spoke assemblies, positioned by said peripheral wall and said annulus, each assembly including an outer member extending radially outward through an opening in the peripheral wall and inwardly through an opening in said annulus and movable radially, a sleeve positioned telescopically on the inner end of said outer member and extending outwardly through said annulus with its inner end normally beyond the inner end of the outer member, and a compressible spring bearing against a head on the outer member and the outer end of said sleeve, being positioned therebetween, and a central floating ring in the casing with its periphery providing a seat for the inner ends of the sleeves.

3. In a resilient wheel the combination comprising a circular casing having a pair of parallel side walls, a circular peripheral wall and a fixed inner annulus coaxial with the peripheral wall, a plurality of spoke assemblies, positioned by said peripheral wall and said annulus, each assembly including an outer member extending radially outward through an opening in the peripheral wall and inwardly through an opening in said annulus and movable radially, a sleeve positioned telescopically on the inner end of said outer member and having arcuate sections extending outwardly through said annulus with its inner end normally beyond the inner end of the outer member, and a compressible helical spring about said outer member and engaging on its outer end a shoulder on the outer member and on its inner end the outer surface of the annulus as well as the outer end of the sleeve, and a central floating ring in the casing with its periphery providing a seat for the inner ends of the sleeves.

EDWARD STIFT.
